METHOD OF AND APPARATUS FOR RADIOSIGNALING.

1,295,245.

Specification of Letters Patent. Patented Feb. 25, 1919.

Application filed January 6, 1916. Serial No. 70,570.

To all whom it may concern:

Be it known that we, ROY A. WEAGANT and HARRY SHOEMAKER, citizens of the United States, residing, respectively, in the town of Roselle, county of Union, State of New Jersey, and in the city of Jersey City, county of Hudson, State of New Jersey, have jointly made certain new and useful Improvements in Methods of and Apparatus for Radiosignaling, of which the following is a specification.

This invention relates to apparatus for radio signaling and consists of a receiving antenna so constructed as to exclude interfering electromagnetic waves of a frequency different from the frequency of the incoming wave to which the receiving apparatus is adapted to respond as in the process of receiving signals due to transmission from a distant station.

In the application of Roy A. Weagant filed on even date herewith, and patented July 23, 1918, Number 1,273,431, it is explained that it is commonly noted that while an aerial or antenna system, by the use of the ordinary tuning methods, can be so adjusted as to respond to a maximum degree to electromagnetic waves having a definite period or frequency, and it is also commonly observed that such an aerial system will oscillate at its own period when excited by electromagnetic waves having a widely different period; this is exceptionally true when such different magnetic waves are quite strong or emanate from a nearby, powerful transmitter. The purpose of this invention is to construct an antenna system which is less responsive to disturbing impulses of a frequency differing from those used for signaling purposes in said antenna system.

The usual arrangement of elevated wire is employed; but included, there are fixed inductances, connected in series from end to end of the antenna wire; these may be of respectively different inductive reaction, or, in other words, the coils differ as regards their size. In any event, whether these coils be of the same or of different inductive

reaction, and whether they be spaced at regular or irregular intervals, their inclusion in the antenna serves to concentrate in them the inductance of the antenna to a considerable extent. Therefore, the inductance of the antenna is not uniformly distributed throughout its length as is the case with the ordinary antenna, up to the point where the tuning devices are inserted, but is, on the other hand, ununiformly distributed. These coils are placed in series in the antenna, one after the other at suitable intervals, and each coil is provided with a shunt branch in which is included a condenser, preferably a fixed condenser. This antenna is associated with a receiving circuit having well known adjustable means for tuning and it results from the construction of the antenna that, when receiving electromagnetic waves of predetermined frequency, waves of higher frequency or shorter wave lengths are effectively excluded, and this is true whether the higher frequency oscillations are due to some interfering transmitter or to natural causes commonly known as "static" interference. The accompanying drawings illustrate the invention. Figure 1 shows the improved receiving antenna; Fig. 2 is a modification; Fig. 3 shows a co-operating transmitting antenna and circuits at a distant point or station. In each figure of the drawing there is an antenna *a*. In Fig. 1 there are a series of inductance coils *i*, these may be closely wound coils of insulated wire and, as shown, coil 5 has the maximum inductance of any of the series of coils *i*. Coil 6 has somewhat less inductance and coil 7 has the least. There is also the usual inducto-rium having a coil 10 in the antenna *a* co-operating with coil 11 in the closed oscillating circuit; coil 11 is bridged by an adjustable condenser 12; there is a detector 14, a telephone receiver 15 bridged by a fixed condenser 16. The details of the receiving arrangement 11 to 16 constitute no part of my present invention; any suitable arrangement may be used. The detector 14 is merely a diagrammatic symbol indicating any detector, for damped or undamped os-

2
cillations, according to circumstances. In Fig. 2 the antenna *a* has a horizontal section 20 of considerable extent suitably supported on towers or other supports 21. Inductance coils *i* of substantially the same construction and relative dimensions as described with respect to coils *i* in Fig. 1 are connected at points in antenna *a*, as described with respect to Fig. 1. In Fig. 3 there is shown a motor generator arrangement 30; the generator is a high frequency alternating generator included in circuit 32 which also includes a Morse transmitting key 33; there is a primary coil of an inductorium 34; this inductorium or converter has a secondary coil 35 and core 36 of magnetic wire; coil 35 is in the closed oscillation circuit with a condenser 37; a quenched spark gap 38 and the primary coil of a transformer 39 having an adjustable secondary coil 40 in the antenna, *a*. The particular construction of the transmitter forms no part of my invention and any transmitter of damped or undamped oscillations may be used, provided, of course, that the damping is not excessive, this being a matter well understood in the art. In the antenna *a* shown in Figs. 1 and 2 each inductance coil *i* is provided with a shunt circuit 50 including a condenser 51. For convenience this may be called a local circuit. Each local circuit, consisting of condenser and inductance, is adjusted to have a natural time period which is different from that of any of the incoming electromagnetic waves with which the aerial is intended to be used; such an arrangement of inductance and capacity in parallel with it connected in series in another electrical circuit namely, the antenna, in this case, has a very high impedance to electrical oscillations whose time period is that to which this inductance and capacity have been adjusted. In fact, if the resistance of this inductance and capacity is zero this impedance or opposition to the flow of current in the main circuit will be infinite; in actual practice if the resistances are small this impedance will be very large. By having a large number of these coils in a single antenna system means are provided which definitely prevent the passage of electrical oscillations having the period of any of these local circuits. It will be seen that by properly adjusting the constants of these inserted devices a wide range of wave lengths can be excluded from the system; for instance, if one combination had a natural period of 600 meters it would effectively exclude wave lengths between, say, 575 meters and 625 meters; the next local circuit would have a period of, say, 700 meters, which would effectively exclude any wave lengths between, say, 675 and 725 meters, and so on. Preferably the longest natural period of any

of these arrangements in a given aerial system is short in comparison to the wave lengths which it is desired to receive; for instance, to receive a wave of 12,000 meters it is undesirable to use any inserted local circuit having a natural period greater than 5,000 meters. 65

During regular, normal operation of the transmitter oscillations of predetermined frequency are apparent in the antenna *a* of the receiving stations Figs. 2 and 3. It will be noted that our improved apparatus provides not only a means for opposing inductive reactions to undesired frequencies by means of inductances, as disclosed in the application of Roy A. Weagant, Serial Number 70,571, referred to above, but that this action is rendered more efficient by the introduction of concentrated inductances of different values at points along the length of the antenna, and that in addition thereto a series of resonant circuits of different constants are arranged throughout the length of the antenna, so that effective opposition to frequencies of certain predetermined values is presented. It results from the arrangement of our invention that if undesired oscillations of a periodicity which does not respond to that of any of the selective opposition circuits is impressed upon the antenna, the disturbing effects of such oscillations may, nevertheless, be eliminated by the action of the concentrated inductances alone in preventing the propagation throughout the antenna of the electromotive forces of such oscillations. 105

120

It will be obvious to those skilled in the art that the above described method and apparatus may be used for avoiding interference from oscillations of undesired frequencies, irrespective of their origin, *i. e.*, whether emanating from neighboring stations, static disturbances, or the station where the antenna is located, and that our invention is applicable to radio telephony as well as to radio telegraphy. 110
115
120

What we claim is:

1. The method of reducing interference from natural electric disturbances when receiving radio messages comprising subjecting received impulses to a plurality of oscillatory circuits each entirely free to oscillate at its natural period and each resonant to a different frequency, and receiving the desired signal impulses in a circuit tuned to a frequency different from each of said circuits. 115
120

2. The method of reducing interference from natural electric disturbances when receiving radio messages comprising subjecting received impulses to a relatively large number of oscillatory circuits entirely free to oscillate at their natural periods and tuned to undesired frequencies. 125

3. The combination at a radio signaling station of receiving apparatus and an antenna associated therewith, said antenna comprising a series of local circuits, each 5 characterized by a different natural frequency than that employed in signaling to said station and being perfectly free to os-

cillate at its natural period, said series containing a relatively large number of circuits as compared to the portion of said antenna associated with said receiving apparatus. 10
